UNITED STATES PATENT OFFICE

2,546,597

DISPENSER FOR TOILET PAPER

Herbert H. Harris, Sacramento, Calif.

Application September 23, 1948, Serial No. 50,855

8 Claims. (Cl. 312—47)

1

This invention relates to new and useful improvements in dispensers and the primary object of the present invention is to provide a dispensing cabinet for rolls of toilet paper and the like.

Another important object of the present invention is to provide a dispenser for toilet paper and the like including a delivery chute, a gravity actuated plate normally closing the entrance to said chute, and embodying novel and improved means for releasably supporting the plate so that the rolls of paper may be delivered to the chute.

Yet another object of the present invention is to provide a dispenser including a novel and improved guide that will receive and retain rolls of paper in a conveniently accessible position.

Another feature of the present invention is to provide a dispenser including a trough adapted to receive rolls of paper, a delivery chute communicating with said trough and embodying means for ejecting rolls of paper from said trough into said chute.

A further object of the present invention is to provide a dispenser of the aforementioned character that is small and compact in structure and which will retain a large quantity of rolls of paper therein in a clean and sanitary manner.

A still further aim of the present invention is to provide a dispenser for toilet paper that is simple and practical in construction, strong and reliable in use, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a group perspective view of the present invention, the lower front wall being removed therefrom;

Figure 2 is a front elevational view of the present dispenser, the lower front wall removed therefrom;

Figure 3 is an enlarged, fragmentary longitudinal vertical sectional view taken substantially on the plane of section line 3—3 of Figure 2;

Figure 4 is a fragmentary longitudinal vertical sectional view taken substantially on the plane of section line 4—4 of Figure 2;

Figure 5 is a rear elevational view of the lower front wall of the present dispenser cabinet;

Figure 6 is a perspective view of the guide and support members used in conjunction with the present invention; and,

2

Figure 7 is a group perspective view of the guide roller and plug therefor that are used in conjunction with the present invention.

Referring now to the drawings in detail, wherein for the purpose of illustration, there is disclosed a preferred embodiment of the present invention, the numeral 10 represents the present dispenser cabinet generally including a pair of spaced side walls 11 and 12, a rear wall 14, an upper wall 16 and a bottom wall 18. The forward edges of the side walls 11 and 12, the upper wall 16 and bottom wall 18 are turned outwardly to provide side flanges 20, an upper flange 22 and a lower flange 24 for a purpose which will later be fully apparent.

The side wall 12 is provided with a downwardly projecting, integral extension or wall 26 which is spaced parallel to a further extension or wall 28 that depends from the inner end 30 of the bottom wall 18 that terminates in spaced relation to the side wall 12.

Suitably fixed to the bottom wall 18, is an elongated substantially concavo-convexed trough 32. The material of the trough 32 immediately adjacent the longitudinal edges 34 and 36 thereof are pressed inwardly to provide channeled strips or retainers 38 and 40 which are spaced parallel to the central portion or lower extremities of the trough 32. The inner end 42 of the trough 32 terminates at the inner portion 30 of the bottom wall 18 (see Figure 1).

The numeral 44 represents a substantially rectangular and hollow block of casing of bendable material having outwardly extending side edges 46 that are integrally formed with a concavo-convexed plate 48. Longitudinal ribs 50 are pressed outwardly from the plate 48 and bear against the concaved surface of the trough 32 for sliding movement of the block 44 relative to and upon the trough 32, as shown best in Figure 3 of the drawings.

A substantially rectangular, lower forward wall 52 is provided with a plurality of apertures 54 that register with further apertures 56 provided in the flanges 20 and 24 and which receive fasteners 58 for detachably securing the forward wall 52 to the side walls 11 and 12, and bottom wall 18 of the housing or cabinet 10. The transverse edges of the wall 52 are turned inwardly to provide retainer flanges 60 that bear against the inner surfaces of the walls 11 and 12, and the lower longitudinal edge of the wall 52 is also turned inwardly to provide a retaining flange 62 that is disposed under the flange 24 of the bottom wall 18.

A bolt of guide pin 64 extends forwardly and

transversely through the block 44 and includes an outwardly projecting threaded end portion 66 that is slidably received in a longitudinal slot 68 in the lower forward wall or panel 52. A finger knob 70 is provided with an internally threaded recess or socket 72 that receivably engages the end portion 66 of the bolt 64.

A substantially rectangular plate 74 is positioned between the forward portion of the trough 32 and the wall 52 and includes an opening 76 that receives the bolt 64 whereby the said plate 74 will move with the block 44.

Projecting downwardly from one longitudinal edge of the plate 74 adjacent one end thereof, is a downwardly and rearwardly extending projection 78 having a holding sleeve 80 at its free lower end in which there is fixed one end of an elongated bar or arm 82. The free end of the arm 82 is angulated as at 84 and terminates in a pointed extremity or cam 86.

Hinged or pivoted to the inner surface of the lower forward wall 52, as at 88, is a gravity actuated support plate 90 that is adapted to close the opening between the end portion 38 of the bottom wall 18 and the side wall 12. One edge of the plate 90 is pressed outwardly to provide a seat 92 that will engage the end portion 36 of the arm 82 when the block 44 is moved toward the side wall 12 to effect a pivotal raising movement of the plate 90 to that position shown in Figure 4 of the drawings.

The extensions 26 and 28 together with a lower wall or cross member 94 between the same form a discharge or delivery chute or bin 96 for a purpose which will later be more fully apparent.

Fixed to and projecting forwardly from the rear wall 14, is a pair of spaced parallel partitions 98 and 100 that divide the cabinet 10 into a pair of side compartments 102 and an intermediate delivery compartment 104 which terminate above the block 44.

Retaining strips 106 are fixed to the forward edges of the partitions 98 and 100 and bottom wall 108 having upstanding flanges 110 close the lower ends of the compartments 102 and support rolls of paper or the like 112 in the compartments 102.

Hinged as at 114 to the side wall 11, is an upper forward wall or closure 116 having inturned edges 118 that will bear against the flanges 26 and 28 when the closure is disposed in a closed position.

Removably secured in the chute 96 is a substantially U-shaped guide and support member 120 having leg portions or side portions 122 that are spaced from the inner surfaces of the extensions 26 and 28. The upper edges of the leg portions 122 are provided with sloping guide surfaces 124 and 126 that terminate in forwardly arcuated guide surfaces 128. Stops 130 are integrally formed at the forward ends of the leg portions 122 and arcuate notches 132 are formed in the edges 128 adjacent the stops 130.

Frictionally fitted in each end of the core 134 for each roll 112, is a suitable plug 136 the outer surfaces of which are provided with recesses 138 in which there are fixed the shank portions 140 of headed rollers 142 that will roll along the surfaces 124, 126 and 128 until the same are received in the arcuate notches 132.

In practical use of the present invention, the block 44 is first positioned adjacent the side wall 11 and the lower roll in the compartment 104 bears upon the trough 32.

As the block 44 is moved toward the side wall

12, the same will force the roll in the trough to a position where the same will be supported by the plate 90 since the plate 90 will be raised by the rod 82 as the block is moved toward the side wall 12.

When the block 44 is again moved toward the side wall 11, the finger or bar 82 will release the plate 90 and the roll will enter the chute 120, it being understood that the rollers 142 will ride upon the edges 124, 126 and 128 as previously described.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A dispenser for rolls of paper comprising a housing, a compartment provided in said housing, a delivery trough adapted to receive rolls of paper from said compartment, a discharge chute, means mounted in said discharge chute adapted to support rolls of paper, means for releasing said last mentioned means whereby a roll of paper will enter said chute, and means supporting said releasing means and constituting a means for urging rolls of paper from the trough into the chute.

2. The combination of claim 1 wherein said means mounted in said discharge chute includes a gravity actuated plate.

3. The combination of claim 2 wherein said releasing means includes a slidable member.

4. In combination, a dispenser housing having a compartment therein, rolls of material in said compartment, a delivery chute, a guide trough leading to the chute, means preventing entrance of said rolls into said chute, means for releasing said last mentioned means whereby said rolls will fall into said chute, means mounted in said chute for guiding and supporting said rolls, means carried by said rolls engaging said guiding and supporting means, and means for urging rolls in the trough toward the chute and constituting a support for said releasing means.

5. A dispenser for rolls of paper comprising a housing having a compartment therein, a horizontally disposed trough disposed beneath the compartment, a delivery chute at one end of said trough, a vertically swingable support plate mounted in said chute, a sliding member mounted in said trough and adapted to force a roll of paper in the trough toward the chute as the member is moved toward the chute, said member blocking the passage of a roll of paper into the trough from the compartment during its movement toward the chute, and means carried by and movable with the member to hold the plate raised during the movement of the member toward the chute, said means releasing the plate as the member is moved away from the chute.

6. The combination of claim 5 wherein said means includes an arm having a cam at one end, said plate having a recess slidably receiving said cam during movement of the member toward the chute.

7. A dispenser for toilet paper comprising a

housing having a vertical compartment, a delivery bin paralleling the compartment and carried by the housing, a trough underlying the compartment and leading to the bin, a vertically swingable plate mounted in said delivery bin, a slide member in said trough for moving a roll of paper entering the trough from the compartment into the delivery bin above the plate, and means carried by said slide member engaging and raising the plate upon movement of the member toward the bin to block the passage of a roll through the bin, and said means releasing the plate upon movement of the member away from the bin whereupon the plate will swing downwardly to permit the passage of a roll of paper through the bin.

8. The combination of claim 7 wherein said means includes an elongated horizontal arm having a cam surfaced end portion, said plate having a recess slidably receiving said cam surfaced end portion upon movement of said member toward said bin.

HERBERT H. HARRIS.
